UNITED STATES PATENT OFFICE.

JOHN A. TOOMEY, OF CHICAGO, ILLINOIS.

CAR-STAKE AND ATTACHING MEANS THEREFOR.

No. 876,415.

Specification of Letters Patent.

Patented Jan. 14, 1908.

Application filed January 28, 1907. Serial No. 354,378.

To all whom it may concern:

Be it known that I, JOHN ANDREW TOO-MEY, a citizen of the United States, and a resident of the city of Chicago, in the county of Cook and State of Illinois, have invented certain new and useful Improvements in Car-Stakes and Attaching Means Therefor; and I do hereby declare that the following is a full, clear, and exact description of the same, reference being had to the accompanying drawings, and to the letters of reference marked thereon, which form a part of this specification.

Though permanently attached car stakes have been heretofore designed and have in some cases been more or less adjustable, these have not gone into use because of evident structural weakness and because of danger resulting from failure to adequately lock in adjusted positions. Furthermore most such stakes are of such construction that the lower end may strike the ground under certain conditions thereby inviting accident. Furthermore while some stakes as formerly constructed are provided with a rest for the stakes in a horizontal position none provide a positive and automatic lock for the stake in said position.

It is an object of this invention to provide attaching means and an adjustable stake, permanently secured therein and positively locked from movement when in its vertical and its horizontal adjustments.

It is a further object of this invention to provide a stake which can only be moved from its vertical position, by first slightly lifting the stake, and which when swung to its horizontal position is automatically locked in said adjustment.

It is a further object of this invention to provide a stake which locks by gravity in all its adjusted positions and is positively secured from vertical movement when in vertical position.

It is also an object of this invention to provide a stake which may slide a predetermined distance relatively the side of the car or other object to which it is attached when turned obliquely with the perpendicular but can never slide or incline sufficiently to touch the ground or road bed even should the locking mechanism be broken or injured, nor turn past the vertical when adjusted from its horizontal position.

It is an important object of this invention to provide a stake holder adapted to firmly

support the stake in its vertical position even should the lock be broken and in which the locking mechanism can be quickly removed in case it or the stake be broken in which event an ordinary wooden stake may be inserted and firmly supported in operative position independently of the locking mechanism.

It is finally an object of the invention to construct the stake and attaching mechanism with few parts, to wholly eliminate springs, and to secure cheapness of construction and simplicity of attachment and in which the parts are not likely to get out of order but if broken can be quickly renewed.

The invention consists in the matters hereinafter described and more fully pointed out and defined in the appended claims.

In the drawings: Figure 1 is a fragmentary side elevation of a car provided with devices embodying my invention. Fig. 2 is an enlarged front elevation of the right swinging stake showing the same in vertical adjustment. Fig. 3 is a view similar to Fig. 2 but with the stake in horizontal adjustment. Fig. 4 is a side elevation of a device embodying my invention with the car sill in section, illustrating one method of engaging the same thereto. Fig. 5 is a top plan view of the left swinging stake. Fig. 6 is a section on line 6--6 of Fig. 5 with part of the stake broken away. Fig. 7 is a view of the same with the stake in horizontal position and the pocket for receiving the end of the stake in vertical section. Fig. 8 is a rear view of one of the rotatable casings or housings. Fig. 9 is an enlarged fragmentary detail of the sill plate taken at one of the bolt holes and with one of the attaching bolts in plate. Fig. 10 is a detail of one of the intermediate stake holders.

As shown in said drawings: A, indicates the side sill of a car to which are rigidly secured sill plates B by means of bolts $b-b'-b^2$ of which the bolts $b-b'$ are arranged near each side the sill plate and near the top thereof and the heads thereof project beyond the face of the sill plate and engage outside of and above shoulders b^3 integral with the plate. The bolts b^2 are secured through the sill plate and sill near the bottom thereof one on each side the center. Said sill plate is constructed of malleable iron, cast steel or any other suitable material and may be of any desired shape to afford a broad bearing on the sill and to project be-

low the same. Said plate B is provided with an integral outward projection at its lower end which is apertured vertically and affords a pocket b^4 for the stake when it is in a vertical position. A housing or casing C is pivotally engaged to said plate B by means of a pivot bolt b^5 which extends through a lug c integral with the casing near its middle and at one side thereof and forms a rotatable stake pocket. The back of said casing or housing is extended on each side thereof and ribbed horizontally to afford strength with light weight and as shown notches c^2-c^3 are provided therein on each side the housing near the upper end thereof to engage the bolts $b-b'$, which acts as stops to limit the adjustment of the stakes in one direction when supported in vertical position. As shown the lateral extension or plate c' on one side the housing is offset and the notch c^3 10 opens on the rear side of the housing which engages around said bolts b' thus supporting the housing in its adjusted position almost independently of the pivot bolt b^5 and not only determines the vertical adjustment but 15 also prevent any tendency to spring outwardly which might otherwise occur with heavy outward pressure from the load.

A gravity lock is provided to engage the stake in its horizontal and its vertical adjustments comprising a lever D which is pivoted to the base plate B by means of a U bolt D' or bolt D^2 and is provided with a curved dog d' which is adapted to extend through a slot d^2 , in the casing or housing. The lower end d^3 of said lever is curved upwardly and inwardly toward the housing and is adapted to extend through a slot or opening in the pocket b^4 in a position to support the stake E when in a vertical position.

The stake is shown as a relatively light I beam or bar, though any suitable material may be used to afford strength and lightness. A block or stop e , is bolted or otherwise firmly secured to the web e' , of said stake in a position to catch under the dog d' , when the stake is in a vertical position at which time the lower end of the stake rests on the end d^3 , of the gravity lever as shown in Fig. 6 thereby preventing vertical movement of the stake either upward or downward except by actuating said lever. To firmly lock the stake in horizontal adjustment the end d^3 , of said gravity lever D, projects above the top of the pocket b , when the stake is lowered and engages the side plate c' , of the housing. As shown said plate is notched to receive the end of the lever which firmly engages beneath the same and prevents movement thereof unless the lever is first actuated.

As shown in Figs. 5 to 7 inclusive the device is adapted for use at the right hand end of the car and the housing or casing C is provided with ribs c^4 to c^6 inclusive of different lengths.

To operate is as follows: The stake is secured to the car by attaching the sill plate thereto, the housing C is then pivoted thereon and the lever D pivoted to the sill plate with the dog d' and end d^3 in the proper place. The stake E with the block or stop e , thereon is then inserted in the housing and dropped to position. To lower the stake, the gravity lever D is pulled out sufficiently for the dog d' to clear the stop e , lifting the stake on the end d^3 sufficiently to clear the top of the pocket b^4 , said stake may then be turned to clear the edge of the pocket and slides by gravity through the casing or housing until the stop c^3 , on the stake contacts with the top of the housing, at the same time the stake is turning to a horizontal position in which adjustment the stake is locked by the end d^3 of the lever D firmly engaging the arm c' of the housing. As shown in Figs. 3 and 7 when the stakes are turned to the horizontal adjustment the right hand stake rests on the dog d' of the lever D and the end abuts against the pocket b^4 and the left hand stake rests on the rib c^5 and the end abuts against the rib c^6 thereby positively limiting the turning movement of the stake to horizontal adjustment and firmly locking the same against movement when in a horizontal position. To raise the stake to a vertical position the lever D is actuated to clear the end of the arm c' and the stake is raised in the housing to clear the top of the pocket b , said stake is then turned until the notches c^2-c^3 in the extension $c-c'$ engage the stops b^3 at which position the stake is in its vertical adjustment and the gravity lock is the position shown in Figs. 3 and 7. The stake is now dropped and its weight bearing against the end d^3 of the lever D forces the same downward and dog d' upward to engage above the stop e on the stake as shown in Fig. 6. It is perfectly obvious that the stake is now positively locked from vertical movement until the lever is again actuated and also that it is firmly supported by the end of the lever D. The stake is also raised to clear the pocket by simply pulling the lever D, the dog d' is then pulled out of the slot and the end d^3 , forces the stake upwardly in which position the end of the lever engages the arm c' when the stake reaches the horizontal position firmly locking the same in that position. Means are provided for limiting the raising of the stake in the housing C and as shown in Fig. 8 for this purpose the back of the housing is slotted and a lug or pin f is rigidly engaged to the stake and engages in the slot when the stake is raised. The stop b^3 affords rigidity for the housing and firmly braces the same against the outward pressure of the load. Should the housing break, the pocket b^4 will firmly carry the stake or any temporary stake until repairs can be made. The stake can never turn sufficiently to touch the

ties or ground even should the locking mechanism break as the stop e^3 limits the drop of the stake and the rests limit the horizontal swing thereby preventing accidents which oftentimes might otherwise occur.

It is necessary with some classes of freight as for instance different lengths of lumber to have stakes closer together than for the standard width. For this purpose a plate or 10 casing G having integral apertured lugs g for securing the same to the car is provided, and loops or rings $g'-g'$ of any shape (as shown rectangular) are pivoted to said plate one near the top and the other near the bottom 15 and a stake is firmly held in place therein owing to the binding engagement of the loops or rings against the same. The plate is notched to receive the upper loop when not in use and the lower loop swings below the 20 plate.

If preferred the web e' of the stake may be slit and expanded to form an integral catch for the dog d' and the steps b^3 may be of different form and removable and rests other 25 than these shown may be used for the stake in horizontal position and many changes may be made without departing from the principles of my invention.

I claim as my invention:

- 30 1. A car stake, means adapted to lock the same when vertically and horizontally extended, said stake slidable relatively of the car when being adjusted to both positions and means preventing longitudinal movement of the stake in horizontal position.
2. A car stake and gravity acting means automatically locking the same in the vertical and horizontal adjustments and supporting the stake in vertical adjustment.
- 40 3. The combination with a car stake of a mechanism adapted to support and automatically lock the stake in vertical and also in horizontal position, said support adapted to be manually actuated to elevate the stake.
- 45 4. The combination with a car of a stake engaged thereto and positively secured from movement when in a vertical position and slidable relatively of the car when turned at an angle with the vertical and means acting to support the stake in vertical position and automatically locking the stake when horizontally extended.
5. The combination with a car of a stake therefor positively secured from movement 55 when in a horizontal and in a vertical adjustment and locking means necessitating lifting the stake before turning to horizontal.
6. The combination with a car of a stake therefor means adapted to lock the stake by gravity from all vertical movement when vertically extended and to automatically lock said stake from movement when turned to a horizontal position and means limiting the horizontal turning of the stake.
- 65 7. The combination with a car of a stake

therefor, means adapted to automatically lock the stake in either a vertical or horizontal adjustment and necessitating lifting the stake when turning from vertical position and means limiting the turning of the 70 stake when adjusted from a horizontal to a vertical position.

8. The combination with a car of a stake engaged thereto adapted to turn to a horizontal position and said stake being slidable 75 relatively of the car before reaching a horizontal position and means whereby said stake is positively locked from movement when in a horizontal position.

9. The combination with a car, of a plate 80 engaged thereto, a pocket integral with said plate, a stake pivotally supported on the car in position for its end to engage in said pocket when in its vertical adjustment, a gravity lock automatically acting to firmly 85 secure said stake from movement when in its adjusted position.

10. The combination with a car of a stake therefor adapted to assume a vertical position only when fully extended, a pocket for 90 the end of the stake when in its vertical position, a rest in said pocket for said stake, a catch engaged to the stake and a lock actuated by the weight of the stake to engage above the catch.

95 11. The combination with a car of a plate rigidly engaged thereto, lugs engaged to said plate, a housing pivoted to said car, arms integral with said housing and having a slot in each adapted to engage said lugs to limit the 100 movement of said housing and means adapted to engage the end of one of said arms adapted to automatically lock the stake in a horizontal position.

12. In a device of the class described the 105 combination with a car of a plate rigidly engaged thereto a housing or casing pivoted to said car and adapted to turn over the face of said plate, a stake slidable in said housing or casing positively secured from movement 110 when in a vertical position and adapted to slide relatively of the casing when turned at an angle with the perpendicular and means adapted to automatically lock said stake when in a vertical or horizontal position. 115

13. The combination with a vertically movable stake of means limiting the turning of the stake to its vertical position and a gravity lock adapted to support and firmly secure the stake from vertical movement. 120

14. The combination with a vertically movable stake, stops limiting the vertical adjustment and means actuated by gravity to support and lock the stake from vertical movement.

15. The combination with a stake, a housing or casing therefor, means engaged to said housing adapted to firmly support and prevent movement of an adjacent stake when in a horizontal position. 125

16. The combination with a car stake and means pivoted to the car to support the end of an adjacent stake and limit horizontal movement thereof.
- 5 17. The combination with a car of a stake therefor, a housing pivoted to the car to receive the same, a pocket adapted to receive the end of the stake therein, means pivoted adjacent the same adapted to support and 10 lock the stake therein when in vertical position and to lock the stake in horizontal position and also support the end of an adjacent stake in horizontal position and means bracing and strengthening the housing and stake 15 when in operative position, said housing adapted to support and prevent longitudinal movement of an adjacent stake when turned to horizontal position.
18. The combination with a car of a stake 20 therefor and means actuated by the weight of the stake to simultaneously support and lock the same from vertical movement.
19. In a device of the class described the combination with a car of a stake engaged 25 thereto, means acting to lock the stake in horizontal position and actuated by the stake to support the same in vertical position.
20. In a device of the class described a 30 stake and attaching means therefor adapted to support the stake in either a vertical or horizontal position, said stake slidable relatively of the car when adjusted to either position and means adapted to automatically 35 lock said stake from movement in both positions.
21. In a device of the class described a stake adapted to slide relatively of the car in adjusting the same to either a vertical or 40 horizontal position and means automatically locking said stake in either position.
22. In a device of the class described the combination with a stake and pivoted support therefor, said stake adapted to move 45 relatively of the support a predetermined distance when the same is adjusted to and from either the horizontal or vertical position and a lever having one end adapted to support the stake in vertical position and 50 lock the same in horizontal position.
23. In a device of the class described the combination with a stake simultaneously 55 movable in a vertical plane and slidable relatively of the object to which attached when adjusted to either a vertical or horizontal position and means actuated by the stake to support and lock the same in vertical position.
24. The combination with a car of stakes 60 therefor adapted to slide relatively thereof, means pivotally supporting said stakes on the car, a lock adapted to lock the stakes in its adjusted positions and means limiting the sliding movement of the stake in both 65 directions.
25. The combination with a car of adjustable side stakes permanently secured thereon and positively supported and locked from movement when vertically or horizontally extended said stakes when moving to either 70 vertical or horizontal position slidable relatively of the car.
26. A car stake, means pivotally supporting the same to the car, a gravity acting lock adapted to lock the stake in horizontal 75 position and adapted to support the end of an adjacent stake.
27. In a device of the class described the combination with a car of a stake therefor, means pivotally supporting the stake, a 80 gravity lock adapted to automatically lock the stake in horizontal position and adapted to lock and support the stake in vertical position.
28. In a device of the class described the 85 combination with a support of a slidable stake pivoted thereto, a pocket rigidly engaged to the support adapted to receive the end of the stake, a lever adapted when actuated to elevate said stake to clear the pocket 90 said stake adapted to swing to a horizontal position and locked in its horizontal adjustment by said lever.
29. In a device of the class described the combination with a car of a stake pivoted 95 thereto, a pocket rigidly engaged to the car adapted to receive the end of said stake, a lever adapted to support the stake in said pocket and when actuated to raise the stake to clear the pocket and adapted to automatically stop and lock the stake when 100 turned to its horizontal position.
30. In a device of the class described the combination with a car of a stake therefor, means pivoting the same to said car, a 105 pocket below the stake, a lever pivoted adjacent the same having its end shaped to support the stake in vertical position to elevate the stake to clear the pocket when the lever is actuated and to lock the stake 110 in horizontal adjustment and a projection engaged to the lever adapted to support the end of an adjacent stake.
31. In a device of the class described the combination with a car of a stake pivoted 115 thereto and slidable relatively thereof, a pocket rigidly engaged to the car and adapted to receive the end of the stake, means pivoted adjacent the pocket adapted to support and to lock said stake in the 120 pocket, said means removable whereby an ordinary stake may be inserted in the pocket.
32. In a device of the class described the combination with a car of a stake pocket 125 rigidly engaged thereto, a stake pivoted above the pocket adapted to fit therein and means pivoted adjacent the pocket to support the stake therein.
33. In a device of the class described the 130

combination with a car of a pocket rigidly but detachably engaged thereto a slideable stake pivoted adjacent the pocket and adapted to fit therein, means supporting the stake in said pocket and means locking the stake in said pocket.

34. In a device of the class described the combination with a support of stake pivoted thereto, a pocket adapted to receive one end 10 of said stake, means pivoted to the car adapted to support the stake in said pocket, said stake and pivotal support adapted to be removed whereby an ordinary stake may be used.

35. In a device of the class described the combination with a car of a housing pivoted thereto, a stake slideable in the housing, a pocket adapted to receive the end of the stake, means supporting the stake in the 20 pocket and adapted when actuated to force the same upwardly to clear the pocket, means limiting the upward movement of the stake, said stake adapted to slide downwardly through the housing when turning to 25 the horizontal position and means limiting the drop of the stake.

36. In a device of the class described the combination with a car of a housing pivoted thereto, a stake slideably engaged in the housing, means limiting the movement of the stake relatively of the housing in each direction and means actuated by the stake to automatically lock and support the same in 30 vertical position.

37. In a device of the class described the combination with a car of a plate engaged thereto, lugs engaged thereto, a housing pivoted to the car above the plate, laterally di-

rected slotted arms engaged to the housing, the slot in each arm adapted to engage one 40 of the lugs thereby preventing the housing turning past its normal position and a stake secured in the housing.

38. In a device of the class described the combination with a car of a plate rigidly engaged thereto, a housing or casing pivoted over the plate, arms engaged to the housing or casing each of which is provided with a slot, projections on the plate, one adapted to fit in each slot to prevent the housing from 50 turning past its vertical adjustment and to strengthen the same and a stake engaged to the housing or casing.

39. In a device of the class described the combination with a car of a housing pivoted thereto, a stake therein, laterally directed arms integral with the housing, means adapted to engage one of said arms to lock the stake in its horizontal adjustment and means adapted to stop the swinging movement of 60 the stake when adjusted to vertical position.

40. In a device of the class described the combination with a car of a stake therefor, means adapted to automatically lock the stake in horizontal position and to support 65 the same in its vertical position, means preventing the stake from turning past a horizontal position and means limiting the movement of the stake when turned to normal.

In testimony whereof I have hereunto subscribed my name in the presence of two subscribing witnesses.

JOHN A. TOOMEY.
